UNITED STATES PATENT OFFICE

IDA ASKEY, OF LORAIN, AND WILLIAM L. CARSON, OF ELYRIA, OHIO, ASSIGNEES OF ONE-FOURTH TO HOWARD H. ASKEY, OF LORAIN, OHIO, AND ONE-FOURTH TO NEVA L. CARSON, OF ELYRIA, OHIO

WEARING APPAREL

Application filed February 21, 1927. Serial No. 169,834.

Our invention relates to an improvement in wearing apparel, and more particularly in a garment having a band adapted to encircle a given part of the body with a snug fit. For example, in a shirt having a divided neck band, it is customary to provide a button hole in each free end of the band to permit the open front parts of the shirt to be buttoned together by a collar button to which a collar may also be attached. A button hole is also provided at the rear of the band diametrically opposite the front button holes to secure the rear part of the collar in place by means of a second collar button. Such shirts are made in various sizes, and merchants are compelled to carry many different patterns of each size to satisfy their customers. Notwithstanding it frequently occurs that the neck band is either too small or too large for the wearer although the body of the shirt may in itself be of the right size to fit. The shape of the neck and shoulders differ so widely in different individuals that a comfortable fit of the neck band, or the correct placement of the collar at the right elevation, becomes impossible or difficult in some cases. Our main object is to eliminate or remedy such troubles by providing an adjustable neck band, one which may be readily sewed upon the shirt in the manufacture thereof, and one which may be adjusted finely to fit the neck with neatness and comfort to permit collars in quarter-sizes to be attached thereto. In making adjustments a further object is to provide a neat take-up or gathering of the goods at separated places in the yoke or shoulder piece of the shirt, and a still further object is to provide a flap member adapted to cover and conceal the adjustable take-up connections for the neck band. The particular construction of neck band and flap also provides a secure means for fixing and holding the collar button in place with only the head thereof exposed for convenient attachment of the collar thereto.

In the accompanying drawing, Fig. 1 is a rear view of a neck band and yoke of a shirt embodying our improvements, the flap being unfolded to disclose the overlapping button-hole extensions which are integral parts of the

divided neck band. Fig. 2 is a rear view corresponding to Fig. 1, showing the flap folded downwardly in overlapping holding position upon and over the buttonhole extensions of the collar band. Fig. 3 is a horizontal section of the collar band on line 3-3 of Fig. 2, and Fig. 4 is a vertical section of the collar band on line 4-4 of Fig. 2. Fig. 5 is a perspective view of the yoke and neck band portion of a shirt, showing the buttonhole extensions of the collar band and flap flexed apart and open.

The present invention comprises a neck band made in two parts 2-2, each of which is sewed at its bottom edge to the border edge of the neck opening which is cut or formed in the shoulder piece or yoke 3 of the shirt. In practice the neck band is formed of narrow flat strips of cloth, comprising two plies of cloth sewed and hemmed together at their upper edges, while the bottom edges are sewed in overlapping relation to the border edge of the neck opening in yoke 3. Yoke 3 is in turn sewed to the main body portion 4 of the shirt and may comprise either a single or double ply or thickness of material. A double ply or thickness of material for the yoke or shoulder piece is desirable in the present instance to prevent ripping or tearing of the goods at predetermined gathering places opposite two flexible buttonhole extensions 5 and 6, respectively, which extend in opposite directions to overlap each other at the rear of a vertical tab member 7 which is formed with a relatively wide foldable flap 8 having a single buttonhole 9 at its center. Flexible extensions 5 and 6 contain a series of laterally spaced buttonholes 10 and 11, respectively, which are adapted to be placed in register opposite buttonhole 9 in the free flap 8 when the said flap is folded downwardly around the buttonhole extensions of the collar band sections 2-2. In this way the buttonhole extensions will be completely concealed and enclosed between tab 7 and the folded flap 8. A neatly rounded top edge 12 is also thereby obtained as a continuation of the upper edge of the collar band, where otherwise a broken joint would appear because of the presence of the overlapping extensions 5 and 6. Fur-

thermore by folding flap 8 around the flexible buttonhole extensions, such extensions will be held in straight alignment and prevented from buckling or turning upwardly with the button as the pivot.

5 Tab 7, having flexible flap 8, is sewed to the upper edge of the yoke portion 3 of the shirt midway between the points or places where the base ends of the flexible buttonhole extensions 5 and 6 are separately sewed to the same edge of the yoke. Furthermore, unsewed gaps or spaces 14-14 are purposely provided between the collar band sections and the side edges of tab 7, and the edge of the 10 yoke which is exposed at the gaps or spaces 14-14 is preferably hemmed to prevent tearing of the goods at these places. The thickness of the goods comprising the yoke at gaps or spaces 14-14 is preferably left thin and 15 pliable to promote folding or gathering, while the added thickness of the band and tab resists buckling or folding at all other points in the edge of the yoke where sewed to the collar band sections 2-2 and tab 7. Accordingly the collar band of the shirt may be 20 made of smaller dimensions (to fit a neck of smaller circumference) by drawing the flexible extensions 5 and 6 towards each other in greater or less degree within the limits or 25 range of adjustment afforded by the buttonholes 10 and 11 when placed in register with each other in pairs opposite the single centrally located buttonhole 9 in free flap 8.

Inasmuch as each collar band section 2-2 30 is sewed separately to the body portion of the shirt in spaced relation to the rear of tab 7 it is obvious that each part may be sewed in place as readily and conveniently as the single and continuous collar band generally used without any change or alteration in the yoke or body part of the shirt itself. However, 35 the front of the shirt and the collar band is open or divided, as usual, to permit the shirt to be slipped on.

40 The invention is not necessarily limited to shirts or garments for men, as it is also of utility in connection with garments for women, regardless of whether a detachable collar is used therewith. To explain further, flap 45 8 serves a very useful purpose in covering and concealing the buttonhole extensions so that this adjustable band may be used in any garment to produce a snug fit and at the same time present a neat and attractive appearance.

50 55 What we claim, is:

A shirt having a yoke portion formed with a neck opening, having a straight border edge, a separate tab portion affixed to and extending upwardly from said border edge at the rear of said opening, collar band sections sewed to the border edge at each side of said opening, each collar band section having a free flexible extension of uniformly reduced width the lower edge being parallelly offset the full length thereof in respect to the upper

edge of said yoke portion, the sewed union of the band sections terminating a substantial distance apart from each side edge of said tab beginning at the offset portions of said sections to provide wide gathering places in the yoke at each side of the tab, the straight edge of the yoke at said spaces being hemmed, each of said flexible extensions being provided with a plurality of button-holes at closely spaced intervals lengthwise thereof, and said tab having a foldable flap provided with a single button hole at its center, said flap being of substantial width to cover all the spaced button holes in said flexible extensions in any adjusted position circumferentially of the band sections.

In testimony whereof we affix our signatures.

IDA ASKEY.
